UNITED STATES PATENT OFFICE.

WILLIAM A. PERVIER, OF WATERTOWN, MASSACHUSETTS, ASSIGNOR, BY MESNE ASSIGNMENTS, TO WILLIAM A. PERVIER, TRUSTEE, OF WATERTOWN, MASSACHUSETTS.

ATTACHMENT FOR CIGARETTE HOLDERS.

Application filed July 28, 1926. Serial No. 125,432.

The invention relates to an attachment for a cigarette holder.

5 The essential object of the invention is to provide an attachment that will function to receive and hold the ash dropping from the cigarette during smoking.

A further object of the invention is to provide an attachment that will function not only as an ash receiver and holder as 10 noted above, but one that also may be converted into a housing for the cigarette holder when not in use.

In connection with the objects above outlined it is my further purpose to provide 15 an attachment attractive in appearance both as an ash receptacle and as a housing for the holder, one that may be easily applied to the holder or disconnected from it, one that can be conveniently and easily changed 20 from an ash receptacle into a housing for the holder, or vice versa, and one that is adjustable in character.

The invention can best be seen and understood by reference to the drawings in which 25 embodiments thereof are shown and in which—

Figure 1 is a side elevation of the cigarette holder fitted with an attachment embodying the invention, but which attachment 30 functions only as an ash receiver and holder.

Fig. 2 is a plan of the same.

Fig. 3 is a longitudinal vertical section thereof.

Fig. 4 is a view partly in side elevation 35 and partly in section of the holder and attachment when occupying a vertical position, showing the capability of a certain element of the attachment for receiving and holding ash when the holder is in a vertical 40 position.

Fig. 5 is a section on the line 5—5 of Fig. 3.

Fig. 6 is a side elevation of a cigarette holder and attachment embodying the invention, 45 which attachment is capable of functioning both as an ash receiver and holder and also as a housing for the cigarette holder when not in use, the attachment being shown functioning as a ash receiver 50 and holder.

Fig. 7 is a section on the line 7—7 of Fig. 6.

Fig. 8 is a side elevation of the parts 55 shown in Fig. 6 excepting that the cigarette holder has been reversed to fit inside the

attachment which has been converted to function as a housing for holding the cigarette holder when not in use.

Fig. 9 is a section on the line 9—9 of Fig. 8, and

Fig. 10 is a front end elevation of the housing as shown in Fig. 8.

Referring to the drawings:

1 represents the cigarette holder. Of this 2 is the mouthpiece, 3 the body of the holder terminating in a fore end portion or butt 5 within which is formed a hole or cavity for receiving the cigarette 6 and to which leads a duct 7 as is customary in such holders.

8 represents the attachment for the holder. 70 The attachment comprises an attaching member 9 in the nature of a ferrule or ring into which the fore end or butt 5 of the holder is adapted to fit, the member 9 simply encircling this butt. The holder is preferably provided with a flange 10 adjacent its butt against which the rear end of the attaching member is adapted to bear, and the attaching member is preferably in length substantially equal to the length of the butt. 80

Connecting with the under half of the attaching member 9 at the fore end thereof (and this preferably by an integral connection) is a primary casing member 11 generally semi-circular in cross section or 85 troughlike in character. This member occupies an underslung position with relation to the attaching member 9 with extension forward thereof beneath the cigarette when borne by the holder. Fitting over the primary member 11 and attached thereto to be 90 slideable thereon telescopically is a secondary casing member 12. This member like the member 11 is generally semi-circular or troughlike in character and functions as an 95 extension to the primary member 11. It is fitted to slide upon the member 11 by means of flanges 13 which turn in over the top edges 14 of the member 11. At its outer end the member 12 is provided with a cupped 100 end piece 15.

With the primary and secondary members 11 and 12 thus connected to one another and arranged beneath the cigarette when in place in the holder, they will operate to catch and hold all ash falling from the cigarette as long as the holder and its attachment are held in horizontal or substantially horizontal position.

In order that the ash may still be re- 110

tained even though the holder be turned down to occupy a vertical position, the cupped end piece 15 of the secondary member 12 is provided with a swinging tray or traylike member 16. This tray fits around the end piece 15 and has its same general form. It is hung to turn on the opposite sides of the end piece 15 on pivots 17, the arrangement being such that when the holder and attachment are turned down to occupy a substantially vertical position, the tray will turn pivotally and occupy a position substantially as shown in Fig. 4 where it is shown co-operating with the end piece 15 to form a receptacle into which the ash may fall and be retained. As the parts are moved back into horizontal position any ash in the tray will fall back into the end piece as the tray swings beneath it.

20 In Fig. 6 a further adaptability of the attachment is shown in that an ash receiver and holder of the general character of that just described is converted to function also as a housing for the cigarette holder when not in use. Excepting that the primary and secondary casing members 11 and 12 are made a little deeper than the same parts shown in the construction just described and excepting, also, for a slight change in the jointed connection between the members, the parts are substantially the same as first described. The members 11 and 12 are made deeper simply by moulding them to have a more precise semi-circular form in cross section so that when the two members are combined, fitting one on top of the other, the two will form substantially a complete circular casing or housing. The telescopic joint between the two members 11 and 12 of the present construction is preferably obtained by providing out-turned flanges 18 on the opposite top edges 14 of the member 11 while the edges of the member 12 are provided with grooved ways 19 slideable on these flanges and by which the member 12 is movable telescopically on the member 11 or removed from it.

With the parts thus arranged as shown in Fig. 6 the attachment will function as an ash holder precisely the same as the form of the attachment first described.

The same parts are convertible to have an arrangement as shown in Fig. 8 where they act as a housing for the cigarette holder when not in use, as follows: It will first be assumed that the entire attachment has been removed from the cigarette holder and the casing member 12 removed from the member 11 simply by withdrawing it from this member. The cigarette holder is then placed within the casing member 11 and the butt end of the holder inserted within the attaching member 9, the position of the cigarette holder being simply reversed from the position ordinarily occupied by it when in

use. The casing member 12 is then slid upon and over the member 11, the two members then combining to form a housing enclosing the holder. The only portion of the holder then left exposed will be a portion at 70 the extreme end of the mouthpiece, and this may be closed by drawing the pivoted traylike member 16 over it substantially as shown in Fig. 8. To then hold the pivoted member 16 in place, it is preferably provided with a clip 20 adapted to engage an indented spring tongue 21 on the forward end of the member 15. The clip and tongue are arranged to have locking engagement with one another only when the members 11 and 12 are combined to form a casing for the holder. The pivoted member 16 is otherwise freely movable around the member 15, the clip 20 then moving along a groove 22 formed in the member 15.

Having thus fully described my invention, I claim and desire to secure by Letters Patent of the United States:—

1. An attachment for a cigarette holder comprising an attaching ring member and a troughlike casing member fixed to the ring member and extending therefrom, said members being adapted and arranged whereby the cigarette holder may be fitted into the ring member by insertion from either end thereof and the casing member serve as an ash receiver for the cigarette held by the holder when the holder is fitted into the ring by insertion from one end thereof and serve as a casing within which the holder lies 100 when the holder is fitted into the ring by insertion from the other end thereof, and a further casing member attached to the casing member first mentioned and covering said holder when the holder is arranged to 105 lie in the first member as aforesaid.

2. An attachment for a cigarette holder comprising an attachable member by which the attachment is secured to the holder, a primary troughlike casing member extending from said attaching member, a secondary troughlike casing member, and means for telescopically attaching the secondary casing member to the primary member whereby it will form either an extension thereof 110 or be convertible to co-operate therewith and form a housing for the holder when not in use.

3. An attachment for a cigarette holder comprising an attachable member by which the attachment is secured to the holder, a primary troughlike casing member extending from said attaching member, a secondary troughlike casing member, means for telescopically connecting said primary and secondary casing members whereby they may be united to form an ash receiver or be convertible to form a housing for the cigarette holder when not in use, and a traylike member pivotally connected to said second- 130

ary casing member and co-operating with said casing members to assist in their formation of both an ash receiver and a housing as aforesaid.

5. 4. An attachment for a cigarette holder comprising an attachable ring, a primary troughlike casing member fixed to the ring and extending from it, a secondary troughlike casing member having a cupped end, a traylike member pivotally secured to the cupped end of the secondary member, and means for telescopically attaching said secondary casing member to the primary casing member whereby all of said members may be combined to form either an ash receiver or be convertible to form a housing for enclosing the holder when not in use, and means for detachably securing said traylike member when functioning to assist in the formation of said housing.
- 10 5. An attachment for a cigarette holder comprising an attachable ring, a primary troughlike casing member fixed to the ring 20 and extending from it, a secondary troughlike casing member having a cupped end, a traylike member pivotally secured to the cupped end of the secondary member, means for telescopically attaching said secondary 25 casing member to the primary casing member whereby all of said members may be combined to form either an ash receiver or be convertible to form a housing for enclosing the holder when not in use, and means 30 for detachably securing said traylike member when functioning to assist in the formation of said housing.
